UNITED STATES PATENT OFFICE.

EDWARD H. JOHNSON, OF BINGHAMTON, NEW YORK.

DESIGN FOR A SPOON.

50,133.

Specification for Design.

Patented Jan. 2, 1917.

Application filed November 1, 1916. Serial No. 129,022. Term of patent 14 years.

To all whom it may concern:

Be it known that I, EDWARD H. JOHNSON, a citizen of the United States, residing at Binghamton, in the county of Broome and State of New York, have invented a new, original, and ornamental Design for a Spoon, of which the following is a specification, reference being had to the accompanying drawing, forming part thereof.

Figure 1 is a plan view of a spoon embodying this design; Fig. 2 is a side eleva-

tion of the bowl and a part of the handle of the spoon shown in Fig. 1.

The bowl of this spoon has formed therein a number of openings of ornamental shape and arrangement as shown.

What I claim and desire to secure by Letters Patent of the United States is:—

The ornamental design for a spoon substantially as shown and described.

EDW. H. JOHNSON.
